STEAM HEATING SYSTEM

Lajos Neményi, now by judicial change of name
Louis Irving Norton, Mount Vernon, N. Y.

Application May 16, 1930. Serial No. 452,910

4 Claims. (Cl. 237—67)

The general object of the present invention is to provide an improved steam heating system of the so-called one pipe gravity return type, in which one or more radiators are supplied with steam from, and return water of condensation to, a single pipe which is vertically disposed and passes the water of condensation which it receives, downward under the action of gravity into the boiler or into a suitable reservoir in which the water of condensation is collected.

More specifically, the object of the invention is to provide a heating system of the type referred to in which the steam supply to each radiator may be regulated in accordance with the desired heating duty of the radiator.

A one pipe gravity return heating system is ordinarily the simplest and cheapest type of steam heating system which can be installed, and such systems are now and long have been in extensive use wherever economy in installation cost is important, and the inherent defects of such a system, as previously constructed, are not prohibitive. Such heating systems as heretofore installed have been open to the objection that they do not permit of any graduated control of the rate at which steam is supplied to the radiator. On the contrary, in such systems as heretofore installed, the steam supply connection to each radiator must always be wide open or fully closed. When an attempt is made to throttle the radiator steam supply connection in such a system, water hammer invariably develops. Even with the steam supply connection wide open, seriously objectionable water hammer frequently develops, particularly when the demand for heat is relatively large and the rate of condensation in the radiator is correspondingly high, as it is when steam is first introduced into a cold radiator.

In the practical use of one pipe heating systems during mild weather or other periods in which less than the maximum heating capacity of the radiator is continuously needed, the steam supply connection to the radiator is ordinarily opened when the need for heat manifests itself by an undue reduction in room temperature, and is closed when the room temperature becomes objectionably high. In general, a building heated by such heating systems is more or less overheated whenever the weather is moderate. Such overheating involves discomfort to the occupants of the building, is unhealthy, and necessarily involves a substantial waste of heat.

In my improved heating system, the steam supply connections to the individual radiators

may be throttled to permit each radiator to continuously receive steam at the rate required to maintain approximately the desired room temperature at all times when sufficient heat can be supplied without using the full heating capacity of the radiator.

To secure that novel result, I make use of two connections between the radiator and the pipe, or riser, from which the radiator receives steam and to which it returns water of condensation. One of those connections is a steam supply connection and includes a regulating device which may be a manually controlled throttle valve or a throttle valve automatically controlled, as by means of a so-called room thermostat. The second connection serves to return water of condensation from the radiator to the pipe, and includes means for maintaining a hydro-seal or water seal in the connection, which is effective to prevent the flow of steam through it into the radiator, even in the extreme condition when the steam supply connection to the radiator is closed and the radiator is cold, but which does not operate to pass water of condensation into the radiator or prevent drainage of the latter under any normal condition of operation.

In my improved heating system each radiator is provided with an air vent which advantageously is controlled by a thermostatic air valve, which may well be of one or another well known form, effective to prevent the discharge of steam through the vent while permitting the escape of air from the radiator when necessary, and permitting atmospheric air to leak into the radiator through the vent to prevent the pressure in the radiator from falling below that of the atmosphere as it tends to, for example, when condensation occurs in the radiator after the steam supply connection to the latter is closed. The water seal in the return connection from the radiator may advantageously comprise a pipe section located below the radiator alongside the riser, and in the space receiving the latter when the latter is enclosed in a building wall chamber of space, as is customary in many installations.

The various features of novelty which characterize my invention are pointed out with particularity in the claims annexed to and forming a part of this specification. For a better understanding of the invention, however, and the advantages possessed by it reference should be had to the accompanying drawing and descriptive matter in which I have illustrated and de-

scribed a preferred embodiment of the invention.

Of the drawing Fig. 1 is a somewhat diagrammatic representation of a portion of a steam heating system; and

Fig. 2 is an elevation partly broken away and in section of a thermostatic air vent valve.

In the drawing A represents the pipe commonly called the riser pipe, employed to deliver

- 10 steam to, and receive water of condensation from one or more radiators B. In the drawing a single radiator is shown, but in many installations, particularly in apartment houses, each riser A supplies steam to, and receives water of condensation from a plurality of radiators located one above another on successively higher floors of a building. The radiator B, as conventionally shown in the drawing, has its steam inlet B' connected to the pipe A by a steam supply branch connection C, including a regulating device, shown as an ordinary hand operated throttle valve C'. Advantageously and as shown, the steam inlet B' is located adjacent the top of the radiator. The radiator is provided with an air vent B², and D is a conventionally illustrated thermostatic air valve which may be of any known or suitable type operating to open the vent B² to permit the discharge of air from the radiator, or to permit atmospheric air to enter the radiator, and to close the vent B² when necessary to prevent the discharge of steam therethrough. The known form of the thermostatic valve D shown diagrammatically in Fig. 1, and in detail in Fig. 2, comprises a body externally threaded at D' to permit the casing to be screwed into the usual nipple opening in the outside of the upper portion of an end section of a steam heating radiator of the usual type with the major portion of the body located within the radiator. The valve body is formed with a passage open at its outer end D² to the atmosphere and terminating at its inner end in a valve seated port D³. The port D³ is controlled by a valve member D⁴ carried at one end of a thermostatic element D⁵. The latter has its opposite end connected to the valve body, and is in the form of a hollow shell having a flexible wall and containing an expandable fluid so that the valve member D⁴ seats and closes the port D³, or moves away from and opens that port, accordingly, as the fluid medium surrounding the shell D⁵ is steam, or is air at a lower temperature than the steam.
- The radiator is shown with an outlet B³ at its bottom for water of condensation. The outlet B³ is connected to the pipe A by a return connection which includes means for maintaining a water seal between the pipe A and the outlet B³ under all normal operating conditions. As shown, the return connection with its water seal means comprises a bent pipe E leading away from the outlet B³ and having a lower depending portion arranged alongside the pipe A, a tubular member E' surrounding the lower depending portion of the pipe E, and a short pipe or nipple E² connecting the upper end of the annular space between the inner wall of the member E' and the outer wall of the depending portion of the pipe E, to the riser A. Said annular space is closed at its upper end and communicates at its lower end with the interior of the pipe E, the lower end e of the latter being slightly above the lower end of the tubular member E'. The lower end of the member E' is provided with a closure which advantageously is

in the form of a plug or cap E³ as shown, which may be detached from time to time, to permit the removal of sand or other foreign matter which may collect in the lower end of the member E.

In installing a heating system of the kind illustrated, each water seal is advantageously initially charged with water, though if not so initially charged with water, it will quickly charge itself with water of condensation, after the system is put into service, and thereafter the seal is constantly maintained by water of condensation forming in the radiator and overflowing through the water seal into the pipe A through the connection E².

The level at which the pipe or nipple E² opens to the pipe A should be sufficiently above the lower end e of the pipe E and sufficiently below the outlet B³ of the radiator to which it pertains, to preserve the water seal in operative condition at all times. To this end the pipe E² should be below the radiator outlet B³ by a distance not less than the head of water corresponding to the maximum excess of pressure in the pipe A above the pressure of the atmosphere, so that when the valve C' is fully closed and the radiator is cold, water of condensation will not be retained in the radiator. The pipe E² should be located above the level of the lower end e of the pipe E by a distance not less than the above mentioned head, so that there will be no tendency to drive all of the water out of the annular space between the member e and the pipe E back into the latter, on any relatively sudden reduction in pressure in the radiator, such as may occur when the valve C' is closed, at a time when the temperature in the room in which the radiator B is located, is much below normal. In practice, of course, the distances just referred to should appreciably exceed said head to provide a suitable safety factor.

With the ordinary mild weather condition of operation in which the valve C' is partly throttled, the pressure in the radiator B will be less than in the pipe A, and the water in the pipe E will then be at some intermediate level H above the pipe E². With the valve C' fully closed, the water in the pipe E will be at a level H' higher than the level H but preferably appreciably below the level of the outlet B³. The difference between the level H' and the level of the outlet B³ represents the normal safety factor. If the normal maximum steam pressure in the pipe A is a pound above that of the atmosphere, the level H' will be above the level of the pipe E by approximately 28 inches. Of course, if the maximum steam pressure of the pipe exceeds the atmosphere by more than a pound, the level of the connection E² must be correspondingly depressed below the level of the outlet B³ and the distance between the pipe E² and the lower end e of the pipe E must be increased over what would be required if the maximum steam pressure were lower.

With the construction illustrated, steam enters and water of condensation leaves the radiator through separate connections, and there is no tendency to water hammer or knocking with resultant objectionable noise and vibration tending to loosen the pipe joints, since the influx of steam is not impeded by, and does not impede the escape of water of condensation, as it may when the steam and water flow in opposite directions through the same passage. The valve

C' may be adjusted to continuously supply steam at whatever rate is needed to maintain a uniform temperature, which is neither too high nor too low, in the room heated by the radiator. In ordinary apartment heating service, the use of the invention results directly in a very substantial saving of heat in comparison with an ordinary one pipe heating system as previously installed, since with the present invention the apartments need not be, and ordinarily are not overheated, while with the ordinary one pipe system, as ordinarily used, the apartments are customarily overheated under mild weather conditions.

With the described provisions for maintaining the water seal in the return connection, the normal excess of pressure in the riser above that in the radiator is never sufficient to cause the sealing water to pass back into the radiator, or to interfere with the free drainage of the radiator. In consequence, there is no tendency for water of condensation to accumulate in the radiator at any time.

The radiator condensing capacity during periods in which less than the full condensing capacity of the radiator is required, is automatically reduced by air then held in the radiator in whatever amount is necessary to make the condensing capacity of the radiator that required to condense the steam then being supplied to the radiator. During any period of steady operation in which steam is being supplied at a rate below the maximum condensing capacity of the radiator the pressure in the radiator will be equal to that of the atmosphere. When the rate of steam supply is increased air is expelled from the radiator as required to maintain or restore atmospheric pressure in the radiator. Conversely when the supply of steam to the radiator is reduced the resultant tendency to the creation of a minus pressure in the radiator sucks atmospheric pressure into the latter until atmospheric pressure in the radiator is restored. The pressure in the radiator never rises above that of the atmosphere except momentarily, until the supply of steam continues to exceed the rate of condensation after the radiator has become filled with steam at atmospheric pressure. In that event, the pressure in the radiator may increase until it equals the pressure in the pipe A.

Since water of condensation does not accumulate in the radiator during any normal condition of operation, the amount of water which can be discharged from the radiator return connection into the riser, when the steam supply to the radiator is substantially increased, is relatively small with suitably proportioned water seal means, and hence does not tend to objectionable water hammer in, or vibration of the riser piping. The amount of water discharged into the riser immediately following an appreciable increase in radiator pressure, is minimized, of course, by reducing the cross sectional areas of the water seal water passages.

The formation of an outlet connection from a radiator to a riser pipe in the manner illustrated, by means of a pipe, like the pipe E, depending into a second pipe like the pipe E', the internal diameter of which is greater than the external diameter of the depending portion of the pipe E, is desirable from the standpoint of mechanical simplicity and low cost of production, and because such an outlet connection

can be readily located closely alongside the riser pipe when the space available for it is restricted. In such an outlet connection the cross sectional areas of the water seal passages, and the water holding capacity of the water seal means, can be reduced to a practical minimum. I have found in extensive use of heating systems of the kind disclosed herein, that the pipe E required for use with an ordinary radiator having as much as seventy five or ninety square feet of radiating surface need not be larger than an ordinary half inch pipe.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:—

1. In a steam heating system the combination with a radiator having a steam inlet, a water of condensation outlet and an air vent, said inlet and outlet being separated from one another to prevent interference by the incoming steam with the outflow of water of condensation, of a vertically disposed pipe adapted to supply steam to and to receive water of condensation from said radiator, a regulable connection between said radiator inlet and said pipe, a separate connection between said radiator outlet and said pipe comprising portions extending downward from said outlet and pipe, respectively, and communicating at their lower ends and forming means for maintaining a water seal in said connection preventing steam flow into the radiator through said outlet, and connected to said pipe sufficiently far below said radiator to provide radiator drainage and to prevent water accumulation in the radiator under all normal operating conditions, and means associated with said air vent closing the latter to prevent the discharge of steam therethrough and opening said vent to permit air to pass into or out of the radiator through said vent.

2. In a steam heating system the combination with a radiator having a steam inlet, a water of condensation outlet, said inlet and outlet being separated from one another to prevent interference by the incoming steam with the outflow of water of condensation, and an air vent, of a vertically disposed pipe adapted to supply steam to and to receive water of condensation from said radiator, a regulable connection between said radiator inlet and said pipe, a separate connection between said radiator outlet and said pipe opening to the latter at a distance below the bottom of the radiator exceeding the normal water head corresponding to the maximum excess of pipe pressure over atmospheric pressure and comprising portions extending downward from said outlet and pipe, respectively, and communicating at their lower ends and forming means for maintaining a water seal in said connection preventing steam flow into the radiator through said outlet, and means associated with said air vent closing the latter to prevent the discharge of steam therethrough and opening said vent to permit air

to pass into or out of the radiator through said vent.

3. In a steam heating system, the combination with a radiator having a steam inlet and an outlet, said inlet and outlet being separated from one another to prevent interference by the incoming steam with the outflow of water of condensation, of a vertically disposed pipe, a connection between said radiator outlet and said pipe, said connection comprising a pipe connected to said outlet and having a depending portion, a second pipe closed at its lower end and larger in internal diameter than the external diameter of the first mentioned pipe and into which said depending portion extends, a connection from the space between the last mentioned pipes and the first mentioned pipe said connection opening to the first mentioned pipe at a distance above the lower end of said depending portion which exceeds the water head corresponding to the maximum excess of pressure in the first mentioned pipe above the pressure of the atmosphere, and means closing said space above the level of its connection to the first mentioned pipe.
4. In a steam heating system the combination with a radiator having a steam inlet, a water

of condensation outlet and an air vent, said inlet and outlet being separated from one another to prevent interference by the incoming steam with the outflow of water of condensation, of a vertically disposed pipe adapted to supply steam to and to receive water of condensation from said radiator, a regulable connection between said radiator inlet and said pipe, a separate connection between said radiator outlet and said pipe providing a flow passage portion leading downward from said outlet and a flow passage portion leading upward to said pipe and opening to the latter at a level below the outlet level, said passage portions being connected at a level below the first mentioned level and providing a water seal in the last mentioned connection, the distance between the first mentioned level and each of the other levels exceeding the water head corresponding to the maximum excess of pressure in the first mentioned pipe above the pressure of the atmosphere, and means associated with said air vent closing the latter to prevent the discharge of steam therethrough and opening said vent to permit air to pass into or out of the radiator through said vent.
